JOHN S. DUNHAM, OF ST. LOUIS, MISSOURI.

Design No. 4,030, dated May 17, 1870.

DESIGN FOR A LABEL.

The Schedule referred to in these Letters Patent and making part of the same

To all whom it may concern:

Be it known that I, JOHN S. DUNHAM, of St. Louis, in the county of St. Louis and State of Missouri, have invented and produced a new and original Design for Labels, of which the following is a specification.

The nature of my design is fully represented in the accompanying drawing, to which reference is made.

The label, as shown in said drawing, is indicative of the biscuit-brand as well as of the manufacturer's trade-mark.

I do not limit myself to the words descriptive of the biscuit or to the words representing my place of

manufacture, but I desire to claim and secure the ornamental design.

Having thus fully described my invention,

What I claim is—

The design for a label, substantially as set forth.

In testimony of said invention I have hereunto set my hand in presence of witnesses.

JOHN S. DUNHAM.
